United States Patent Office.

FÉNÉLON VIÉ, OF HAVRE, FRANCE.

Letters Patent No. 89,816, dated May 4, 1869.

IMPROVEMENT IN LIFE-BOATS.

The Schedule referred to in these Letters Patent and making part of the same.

To all whom it may concern:

Be it known that I, FÉNÉLON VIÉ, of Havre, in the Empire of France, have invented a new and improved Life-Boat; and I do hereby declare the following to be a full, clear, and exact description thereof, which will enable those skilled in the art to make and use the same, reference being had to the accompanying drawing, forming part of this specification, in which drawing—

Figure 1 represents a sectional side elevation of this invention when extended.

Figure 2 is a plan or top view thereof.

Figure 3 is a transverse section thereof.

Figure 4 is an end view of the same when folded up.

Similar letters indicate corresponding parts.

This invention consists in the arrangement of ribs or frames, the ends of which are bifurcated, or provided with large gore-shaped openings, in combination with a covering and lining of India-rubber cloth, or some other flexible and water-tight material, and with longitudinal rods or braces, in such a manner that when the covering is secured to the outside and the lining to the inside of said bifurcated ribs or frames, a series of air-spaces are formed, communicating with each other through the gore-shaped openings in the frames, and by securing the longitudinal braces in position, a boat is obtained of considerable buoyancy, which, when said braces are removed, can be folded up in a comparatively small compass. The braces are secured between flanges, attached at the proper places to the covering of the boat; and the ends of said covering are so formed that the same, when extended and fastened to the longitudinal braces, will form two additional air-chambers at both ends of the boat, whereby the buoyancy and the safety of said boat are materially increased.

A represents my life-boat, which is constructed of a series of ribs or frames, B, and a covering, C, and lining, D, of India-rubber cloth, or some other watertight and flexible material.

The ribs B are made, by preference, of sheet-metal, and they are provided with large gore-shaped openings, a, near both ends, as clearly shown in fig. 3 of the drawing.

The covering C is stretched over the outside edges of said ribs, and the lining D is secured to their inside edges, and it extends over the top of said ribs and connects with the covering, so that said lining and covering practically form one continuous sheet of waterproof material, the two being further connected by double-flanged pieces b, as shown in fig. 1, which also serve to hold the lining and covering in the proper position in relation to the ribs.

When the covering and lining are properly adjusted on the ribs, as previously described, a vessel or trough is formed, which can be extended to the position shown in figs. 1 and 2, or folded up to the position shown in fig. 4; and when it is extended, it is held in position by longitudinal braces E F, two of which are fastened to the edges of the gunwales and one to the bottom of the vessel, as shown. These braces are held in position by flanges c, which are secured to the covering, and provided with eyelets to receive cords, by means of which said braces can be tied down, so that they are not permitted to shift, and that they will retain the vessel firmly in its extended position.

The ends of the vessel or trough are closed by air-chambers G, which form integral parts of the covering and lining, and which are held in their extended position by hinged braces, d, as shown in fig. 1.

When the boat is folded up, these braces turn down to the sides of the last ribs, and when the boat is extended, the tops of the air-chambers are also secured to the longitudinal braces E, and thereby retained in the required position.

It will be seen that when my boat is extended, a series of air-chambers is formed between the ribs, and these air-chambers communicate with each other through the gore-shaped openings a, and the buoyancy and safety of the boat are still further increased by the air-chamber G at the ends.

When the boat is not used, it can be folded up and stored away in a comparatively small space.

Having thus described my invention,

What I claim as new, and desire to secure by Letters Patent, is—

1. The ribs B, with gore-shaped openings a, in combination with the covering C and lining D, and with the longitudinal braces E F, substantially as herein shown and described.

2. The double flanged pieces b, in combination with the lining D, covering C, and ribs B, substantially as and for the purpose set forth.

3. The flanges c, in combination with the longitudinal braces E F, covering C, and lining D, substantially as and for the purpose described.

4. The air-chambers G, in combination with the longitudinal braces E, covering C, lining D, and ribs B, substantially as and for the purpose set forth.

This specification signed by me, this 18th day of September, 1868.

F. VIÉ.
